TRIPLE DRESSER

Melbourne F. Smith, Jr., 101 Maehill Drive, Lenoir, N.C.

Filed Jan. 15, 1964, Ser. No. 78,213

Term of patent 14 years

(Cl. D33—6)

The back of the triple dresser is substantially plain and unornamented.

I claim:

The ornamental design for a triple dresser, as shown and described.
